UNITED STATES PATENT OFFICE.

MAURICE H. SCHILLER, OF CHICAGO, ILLINOIS.

COMBINED VEST AND BELT ATTACHMENT.

1,304,382.

Specification of Letters Patent.

Patented May 20, 1919.

Application filed October 7, 1916. Serial No. 124,212.

To all whom it may concern:

Be it known that I, MAURICE H. SCHILLER, a citizen of the United States, residing at Chicago, in the county of Cook and State of Illinois, have invented certain new and useful Improvements in Combined Vest and Belt Attachments, of which the following is a specification.

My invention relates to garments, and 10 more particularly combined vest and belt attachments.

The object of my invention is the provision of a simple and efficient belt and vest member or attachment which is comfortable 15 in use, and one which may be easily and quickly put on and taken off. Other objects 20 will appear hereinafter.

An embodiment of my invention is shown in the accompanying drawings forming a 25 part of this specification, and in which—

Figure 1 is a front view of a coat equipped with my vest and belt attachment.

Fig. 2 is a rear view of the same.

Fig. 3 is an enlarged section taken at the 25 belt line of the coat.

Fig. 4 is a front view of a coat with my belt and vest attachment secured thereto in a different manner than that shown in Fig. 1.

Fig. 5 is an enlarged section taken at the 30 waist line of the arrangement shown in Fig. 4.

Fig. 6 is an enlarged fragmental view of a portion of the belt and vest attachment as applied to a coat.

Fig. 7 is a fragmental section taken on line 7—7 of Fig. 6.

Fig. 8 is a slightly modified form of belt with a corset attachment thereon.

Fig. 9 is an enlarged section taken on line 40 9—9 of Fig. 8.

Fig. 10 is a front view of the belt shown in Fig. 9 with vest front and corset attachments thereon.

Fig. 11 shows my improved vest attachment forming the lower part of a complete vest; and

Fig. 12 is an enlarged fragmental section taken on line 12—12 of Fig. 11.

Referring more particularly to the drawings, I have shown a coat in Figs. 1, 2 and 3 which may be of any conventional design. The form shown is an outing or light unlined coat. In this form of coat, which usually has a belt, I provide openings 15 at 55 its sides at the waist line thereof. Through these openings I dispose my belt member 16

so that the back portion of the belt is disposed around the back of the coat 17. Since the belt passes through the openings 15, it is held against slipping downwardly on the 60 coat. The ends 18, of the belt 16, extend into the coat under the front portion 16' thereof. On the ends 18 of the belt, I provide a plurality of buttons 19.

My vest front attachment preferably 65 comprises two portions 20, detachably secured together at their adjacent front edges by button and buttonhole connections 21. The rear ends of the vest attachment are provided with buttonholes 22, which are adapted 70 to engage certain of the buttons 19. The arrangement is such that by engaging the buttonholes 22 on the different buttons 19, the size of the combined vest front and belt may be varied, as will be readily understood 75 upon reference to Fig. 3. Any other form of connection between the rear ends of the vest front 20 and the front ends 18 of the belt may be provided, when so desired, without departing from my invention.

In Figs. 4, 5, 6 and 7 I have shown my 80 combined vest and belt attachment applied to a coat which does not have a belt exposed across its back portion. When it is desired to connect the combined belt and vest attachment to the coat, I provide openings 23, in the lining 24 of such a coat. The openings 23 are preferably at the sides of the lining at the waist line thereof so that the belt 16 will be disposed between the lining 24 and the outer part 25 of the coat. In this 85 form the ends 18 extend through the openings 23 to the inside of the coat where they are attached by means of buttons 19 and buttonholes 22 to the vest front 20. It will 90 be noted that the vest front portions have substantially straight lines at their upper ends, and are substantially continuous lines of the upper edge of the belt portion. This is the preferred form, but these lines may 100 be varied as desired. It will be apparent that the vest and belt attachment may be used entirely inside of the coat and not connected thereto in any manner.

In Figs. 8, 9 and 10, I have shown a modified form of belt member. In this construction the belt member is made up of material forming the inside and outside covering 26. The inner and outer sides 26 are held in flat or spread out conditions by a piece of canvas 27, or other suitable material, which is of sufficient size to hold the sides 26 in 105 110

proper condition. The inner side 26 is preferably stitched along its central portion to the stiffening member 27 by stitchings 26'. The front portion 28 of the belt is formed 5 considerably narrower than the rear portion and is adapted to pass under the vest portion 20. The front ends of the narrow portion 28 are joined by a buckle 28', or its equivalent, so that the belt can be adjusted to different sizes. To further strengthen the rear or wide portion of the belt, I provide stiffening stays 29, which may be of whalebone, or any other suitable substance. At the rear of the inner side 26, I provide loops 30 which 10 are adapted to engage the trouser buttons, not shown, of the wearer to hold the belt in proper position. The front ends of the wide portions are provided with buttons 19', which the buttonholes 22 are adapted to engage to secure the vest attachment 20 to the belt. It will be apparent that with this form of belt, that the openings 15 and 23 must be made larger than where the belt is narrow, as shown in Figs. 1 and 4. It will also 15 be apparent that with the form of belt shown in Figs. 8, 9 and 10, the attachment may be used without regard to the coat. The wide belt part of the last-mentioned form of belt provides a belt which is wide 20 and comfortable in use.

In Figs. 11 and 12, I have shown my vest and belt attachment making up parts of a complete vest. In this form, the vest and belt attachment are substantially the same 25 as shown in the previous figures and form the lower part of the vest. The upper portion 31 of the vest front is made in the usual manner and provided with a back 32. The lower front edge of the portion 31 is 30 preferably buttoned over the top button 21 of my vest front attachment to hold the upper and lower portions of the vest together. To better hold these upper and lower portions together, I provide a flap 33 on my 35 vest front attachment or lower portion which is adapted to button onto buttons 34 secured to the under side of the upper portion 31. Any form of button connections may be supplied to join the upper and lower portions together, the form I have shown be-

ing the conventional clasps. The button and buttonhole arrangement 19 and 22 between the vest front attachment 20 and the belt 16 provide means for varying the size of the waist line of the complete vest shown 55 in Fig. 11, as will be readily understood.

While I have illustrated and described the preferred forms of my invention, I do not desire to be limited to the exact details set forth, but desire to avail myself of such variations and changes as come within the scope of the appended claims.

I claim:—

1. In combination, a coat; and a vest attachment removably secured to the coat. 65
2. In combination, a coat having openings therein; a belt member having its ends extending through said openings; and a vest attachment attached to the ends of the belt member. 70
3. In combination, a coat; a belt member attached to the coat; and a vest attachment secured to the belt member inside of the coat. 75
4. In combination, a coat having openings in its sides at the waist line thereof; a belt member extending through said openings; and a vest attachment having its ends buttoned to the ends of the belt member. 80
5. In combination, a coat having openings in its sides at its waist line; a belt member having its central portion disposed around over the back part of the coat and its ends extending through said openings; and a vest member secured to the ends of the belt member on the inside of the coat. 85
6. In combination, a coat having openings in its sides at its waist line; a belt member having its central portion disposed around over the back part of the coat and its ends extending through said openings; and a vest member removably and adjustably secured to the ends of the belt member on the inside of the coat. 90

In testimony whereof I have signed my name to this specification on this 5th day of October A. D. 1916.

MAURICE H. SCHILLER.
